HANDLE FOR KITCHEN TOOLS OR THE LIKE

James L. Hvale and Robert A. Eckersberg, Chicago, Ill., assignors to Ekco Products Company, Chicago, Ill., a corporation of Delaware

Filed Apr. 17, 1961, Ser. No. 64,779

Term of patent 14 years

(Cl. D44—29)

FIG. 1 is a side elevational view of a handle for kitchen tools or the like showing our new design.

FIG. 2 is a reverse side elevational view thereof.

FIGS. 3, 4 and 5 are vertical sectional views taken along lines 3—3, 4—4 and 5—5 of FIG. 1, respectively.

We claim:

The ornamental design for a handle for kitchen tools or the like, as shown.
